US00D883321S

(12) **United States Design Patent** (10) Patent No.: **US D883,321 S**
 Clymer et al. (45) Date of Patent: ** May 5, 2020

(54) **DISPLAY SCREEN OR PORTION THEREOF WITH GRAPHICAL USER INTERFACE**

(71) Applicant: **Lutron Technology Company LLC**, Coopersburg, PA (US)

(72) Inventors: **Erica L. Clymer**, Northampton, PA (US); **Praneetha Jonnala**, Allentown, PA (US); **James Mathias Weber**, Allentown, PA (US); **Jennifer Wong**, Breinigsville, PA (US)

(73) Assignee: **Lutron Technology Company LLC**, Coopersburg, PA (US)

(**) Term: **15 Years**

(21) Appl. No.: **29/689,882**

(22) Filed: **May 2, 2019**

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design.

1 Claim, 1 Drawing Sheet
